UNITED STATES PATENT OFFICE

143,821

DESIGN FOR A WRIST WATCH STRAP

Nicholas N. Holmsky, New York, N. Y.

Application January 4, 1945, Serial No. 117,248

Term of patent 3½ years

(Cl. D45—4)

To all whom it may concern:

Be it known that I, Nicholas N. Holmsky, a citizen of the United States, residing at New York, in the State and county of New York, have invented a new, original, and ornamental Design for a Wrist Watch Strap, of which the following is a specification, reference being had to the accompanying drawing, forming part thereof.

Fig. 1 is a plan view of a wrist watch strap, showing my new design with a portion thereof broken away; and

Fig. 2 is a side view of the same.

The dominant features of the design are shown in full lines, the fragmentary broken line indication of a watch being for illustrative purposes only.

I claim:

The ornamental design for a wrist watch strap, as shown and described.

NICHOLAS N. HOLMSKY.
